UNITED STATES PATENT OFFICE.

KALMAN FOLDEAK, OF BROCKVILLE, ONTARIO, CANADA.

GARBAGE-RECEPTACLE.

1,176,046.

Specification of Letters Patent. Patented Mar. 21, 1916.

Application filed May 19, 1915. Serial No. 29,240.

To all whom it may concern:

Be it known that I, KALMAN FOLDEAK, a subject of the King of Hungary, residing at Brockville, in the Province of Ontario and Dominion of Canada, have invented certain new and useful Improvements in Garbage-Receptacles, of which the following is a specification.

This invention relates to certain new and useful improvements in garbage receptacles.

The primary object of this invention is to provide a fireproof odorless garbage can having a foot operated closure member, the entire structure being easy and inexpensive to manufacture.

A further object of the invention is to provide a metallic receptacle having a closure lid and a specially housed novel form of foot operated actuating means therefor, and a removable mounting means being provided for the lid.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like designating characters refer to corresponding parts throughout the several views:

Figure 1 is a vertical central longitudinal sectional view of the device, the lid and its actuating means being shown by dotted lines in their open positions. Fig. 2 is a rear elevation of the device with the side housing partially broken away. Fig. 3 is a top plan view thereof, and Fig. 4 is a perspective view of the bottom mechanism housing detached.

While the present invention is adaptable for various forms of garbage and other receptacles, the same is herein illustrated in connection with a metallic cylindrical can 10 having a closure lid 11 hinged to a rear cover section 41 as at 12 and provided with a partial length edge flange 13 adapted for overlying the front portion of the edge of the can. The cover portion 41 has a depending flange 42, overlying the can edge, while hooks 43 pivoted to the flange 42 engage staples 44 carried by the can. A centrally arranged inwardly projecting lug 45

is carried by the flange 42 and seats within a notch 46 in the upper edge of the can.

An operating lever 14 is flatly secured to the outer side of the lid 11 and has an angular rear extension 15 terminating in an open hook 16 positioned in substantial alignment with the rear edge of the can. A housing 17 of the form best illustrated in Fig. 4 is diametrically positioned at the bottom of the can 10 interiorly thereof and has an inverted U-shaped bottom 18 of the can surrounding the top and opposite sides thereof, while the said housing is attached to the opposite sides of the can by flanges 19 carried by the housing. The elongated chamber 20 within the housing communicates with a slot 21 positioned through the front side of the can and adjacent the bottom thereof, while a similar slot 22 communicates with the chamber 20 at the rear of the can 10 being arranged through the side thereof. A bottom plate 23 may also be provided for the housing chamber 20 and secured to the opposite base flanges 24 of the said housing by means of rivets 25.

An operating rod 26 is slidably mounted longitudinally of the can 10 and at the rear thereof, being positioned within a rear longitudinal side housing 27. A connecting link 28 is hinged to the upper end of the rod 26 as at 29 and is provided with a slot 30 engaging over the lever hook 16. A foot lever 31 is positioned within the chamber 20 of the housing 17 being pivoted upon a rod 32 extending through opposite perforations 33 in the said bottom housing, while the forward pedal end 34 of the said lever 31 extends outwardly of the can through the aforementioned slot 21.

A rocker arm 35 is pivoted upon a rod 36 which extends through opposite perforations 37 of the base housing 17. The rocker arm 35 is provided with a foot 38 resting in normal contact with an arm 39 of the said lever 31, while a link 40 pivotally connects the free end of the rocker arm 35 to the lower end of the operating rod 26, it being noted that the said link 40 and connecting end of the arm are slidably positioned through the rear slot 22 of the can 10.

In operating the device, it is intended that the person desiring to deposit refuse within the can 10 approaches the front side thereof and depresses the lever pedal 34 by means of his foot which tilts the rocker arm 35 drawing

downwardly the operating rod 26 and thereby opening the lid 11 to the position illustrated in dotted lines in Fig. 1. Upon releasing the foot from the pedal 34, the 5 weight of the elements allows the lid to automatically close and the mechanism to return to its normal rest position.

A serviceable and inexpensive garbage can is thus provided which is substantially 10 odorless and the above arrangement insures the normal closing of the cover as the link 28 prevents the closure member 11 from moving to an upright position where the same could by any possibility remain open 15 after the foot pedal 34 is released. It is to be understood that the housing 17 being covered by the can bottom 18, consumes but slight space within the can, the garbage being positionable upon the opposite sides 20 thereof, while opposite spaces are formed between the housing 17 and the can bottom which will accommodate any projecting ends 25 of the pivoting rods 32 and 36. The lid 11 and cover 41 are removable by disengaging the hooks 43, when desired to empty the can.

While the form of the invention herein shown and described is what is believed to be the preferred embodiment thereof, it is nevertheless to be understood that minor 30 changes may be made without departing from the spirit and scope of the invention as set forth in the claims.

What I claim as new is:—

35 1. A device of the class described comprising a can, a hinged closure lid thereon, an angular lever outwardly secured to the said lid and terminating in a hook at the side of the can, the said can being provided with slots in the front and rear thereof, a housing

positioned within the said can and provided 40 with a chamber communicating with the said slots, a housing longitudinally secured to the side of the can and communicating with the said chamber, an operating lever within the said bottom housing and having 45 a forward pedal end extending through said front slot, an operating rod slidably mounted within the said longitudinal housing, a perforated link mounted upon the said hook and pivotally connected to the upper end of 50 the said operating rod, a rocker arm pivoted within the said bottom housing and having one end normally engaging the said operating lever, and link connections between the outer end of the said rocker arm and the 55 lower end of the said operating rod shiftably movable through the said rear slot, and an inverted U-shaped bottom within the can positioned overlying the said bottom housing. 60

2. A device of the class described comprising a can, a hinged closure lid thereon, a bottom housing within said can having a chamber therein and attaching side flanges, an inverted U-shaped bottom within the said 65 can overlying the said housing and flanges and providing opposite spaces therebetween, foot operated lever and arm mechanisms within the said housing, pivoting rods for 70 the said mechanisms projecting through the opposite sides of the said housing within the said spaces, and operative connections between the said mechanisms and the lid.

In testimony whereof I affix my signature.
KALMAN FOLDEAK.
